US0D1045282S

(12) **United States Design Patent** (10) Patent No.: **US D1,045,282 S**
(45) Date of Patent: ** Oct. 1, 2024

(54) **PIPE CLEANER**

(71) Applicant: **Lei Zhang**, Beijing (CN)

(72) Inventors: **Lei Zhang**, Beijing (CN); **Dabao Zhang**, Beijing (CN)

(73) Assignee: **Lei Zhang**, Beijing (CN)

(**) Term: **15 Years**

(21) Appl. No.: **29/891,919**

(22) Filed: **May 11, 2023**

(51) LOC (14) Cl. **15-05**

(52) U.S. Cl.

USPC **D32/14; D8/358**

(58) **Field of Classification Search**

USPC D32/1, 14, 25, 35; D8/14, 310-320, 356,

(57) **CLAIM**

The ornamental design for a pipe cleaner, as shown and described.

DESCRIPTION

FIG. 1 is a perspective view of a pipe cleaner showing our new design;

FIG. 2 is another perspective view thereof;

FIG. 3 is another perspective view thereof;

FIG. 4 is another perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is an enlarged view of portion 11 shown in FIG. 2;

FIG. 12 is an enlarged view of portion 12 shown in FIG. 2;

FIG. 13 is an enlarged view of portion 13 shown in FIG. 2;

and,

FIG. 14 is an enlarged view of portion 14 shown in FIG. 3. The dash-dash broken lines in the drawings depict portions of the pipe cleaner that form no part of the claimed design. The dot-dash broken lines represent boundaries of the enlarged portions and form no part of the claimed design.

1 Claim, 14 Drawing Sheets
